UNITED STATES PATENT OFFICE

CHARLES W. STOUT, OF BROOKLYN, NEW YORK, ASSIGNOR TO AINSLIE KNITTING MACHINE CO. INC., OF BROOKLYN, NEW YORK, A CORPORATION OF NEW YORK

PROCESS OF AND MACHINE FOR KNITTING CAPS AND THE LIKE

Application filed July 29, 1930. Serial No. 471,457.

This invention relates to process and machine for knitting caps and more particularly to a process and machine in which the cap is knit by reciprocatory knitting of a plurality of segments radiating from the crown toward the hatband of the cap. The invention will be shown and described in the making of a beret cap on a circular knitting machine by reciprocatory knitting.

10 One object of the invention is the production of a beret cap on the ordinary seamless hosiery machine.

In the drawings the invention will be illustrated in connection with the well known 15 Scott & Williams type of revolving needle cylinder seamless hosiery machine.

Fig. 1 is an elevation from the left side 20 of a Scott & Williams machine, partly broken away, embodying the invention showing the main pattern drum and the various knitting cams and pickers controlled by it;

Fig. 2 is a plan view of the needle circle 25 showing the needle butts and the cams which act on them, the needle cylinder having just completed the oscillation in the clockwise direction corresponding to course 20;

Fig. 3 is a development of the needle cylinder and knitting cam cylinder with the needles at the beginning of the oscillation in 30 the clockwise direction referred to in Fig. 2, as indicated by the arrow;

Fig. 4 is a development similar to Fig. 3 with the needles at the end of the oscillation in the counter-clockwise direction following 35 the course of Figs. 2 and 3 i. e. course 19. The arrow indicates the direction of movement for knitting course 19;

Fig. 5 is a schematic representation of one 40 method of manipulating the courses and needles in successive segments of a cap in accordance with the invention, the knitting progressing from bottom to top of the figure;

Fig. 6 is an elevation, viewed from the 45 center of the machine, of the switch cam and the widening or down picker;

Fig. 7 is a vertical sectional view through 50 the widening picker and the adjacent part of the needle cylinder showing the blind needle just before it is lowered;

Fig. 8 is a view similar to Fig. 7 just after the blind needle has been drawn down;

Fig. 9 is a plan view of the throat plate and needles taken with the parts at the same position as in Fig. 7; while

55

Fig. 10 is a view from the lower side of the fluted guard which holds the fabric down.

One of the difficulties of knitting beret caps has heretofore been the expense and labor of obtaining segments of the proper shape 60 and joining them together. According to my invention the segments are knit in integral succession, of the proper shape and completely joined together in a process of reciprocatory knitting which leaves a selvedged 65 edge for the hatband and only requires the looping together of the first and last courses of the cap and the single loops at the crown.

The machine will be described first. The example shown in the drawings is of the general type described in the U. S. patent to Robert W. Scott, 1,152,850 dated September 7, 1915. It has the usual needle cylinder 70 260 adapted to turn in the head of the machine but since the entire cap is produced 75 by reciprocatory knitting the cams on the clutch shifting drum are set to drive the clutch in an oscillatory manner at all times. The needle cylinder contains independent

latch needles *n* in slots cut in the cylinder 80 as usual but there is one segment of the circle in which the needles are omitted. Thus, for instance, if there are 136 slots in the cylinder there may be only 90 needles. According to 85 Figs. 2, 3 and 4 these needles are divided into several groups as follows: a so-called hatband group of 18 needles *H* each having a long butt; a so-called ever active group of 37 needles *E* each having a medium butt, and a so-called crown group of 34 needles *C* each 90 having a medium butt. In the example shown in the drawings these groups appear in the order named when read in a clockwise direction from above as in Fig. 2, the empty slots lying together as a gap in the needle 95 circle being between the crown group *C* and the hatband group *H*. I prefer to have an extra needle *B* at the gap end of the hatband group and to make this needle one with a long butt like the hatband group. It may 100

be a so-called "blind" needle, i. e. one with a shank but with its head cut off. This completes the 90 needles. The needles are caused to knit by the usual right and left hand stitch cams 360, 361 and draw down cam 357 located at the knocking-over point. These three cams are substantially the same as those shown in the above-mentioned patent to Robert W. Scott 1,152,850. Associated with the right and left hand stitch cams 360, 361 are pivoted narrowing or up picks 650, 651 held together for interrelated movement first in one direction and then the other by a link 667 all in the usual manner. The left hand up pick 651 is long enough to lie in the path of the medium length needle butts when its operative end is swung to the left, but the right hand up pick 650 is not quite so long and when swung into its operative position in the notch on the upper surface of the right hand stitch cam it allows the needles having medium length butts to pass it and engages only the leading active long butt needle.

Cooperating with the narrowing or up picks 650, 651 is a peculiar widening or down picker 680 located at the front of the machine as usual and mounted in the usual manner. As shown in Figs. 2 and 6 this pick is notched to receive needle butts on only one side and on the other side it is rounded off to allow needle butts to pass it with the least resistance. It is shown notched on the left side as it is mounted in the machine and therefore it can only engage and lower needles when they are moving in a counter-clockwise direction. It should be noted that this pick is shortened to permit free passage to needle butts of medium length and that in the example given in the drawings the lips of the narrowing picks 650, 651 and the widening picker 680 are wide enough to engage only one needle at a time. As in the above mentioned Scott Patent 1,152,850 the widening picker 680 is moved from operative to inoperative levels at the necessary times in the knitting by a vertical gravity rod 216 controlled from the main pattern drum 120 of the machine. I prefer to provide two heights of cams on the main pattern drum 120 to control the gravity rod 216 the high and low cams 501, 502 allowing the widening picker 680 to lie at its uppermost or operative level where it will engage long needle butts at the inactive level as specified, and the surface of the pattern drum holding the picker below such inactive needle butt level where the picker will be idle.

For the purpose of moving needles as a group between the inactive level and the active level a switch cam 415 is provided between the right hand stitch cam 360 and the widening picker 680. This switch cam is very close to the picker and its point faces toward the stitch cam 360 rather than to-

ward the picker as is usually the case. Its principal function, in the manufacture of the specific cap whose manufacture is being taken as an example of the invention, is to lower needles as a group from the inactive 70 to the active level while the needles are moving in a clockwise direction. The machine is so adjusted that the switch cam can operate in this manner on both the hatband and crown groups on the same oscillation of the 75 machine.

In order to do this the switch cam is so located with reference to the end of the counter-clockwise movement that the hatband group of needles has just passed the switch cam at the end of an oscillation in that direction. The needles are now ready to move in the clockwise direction and as shown in Fig. 3. The hatband group are lowered at the beginning of this clockwise course, i. e. course 85 20, and knit at the end of the movement, while the crown group of needles reach the switch cam and are lowered by it after they pass the knitting cams and they therefore knit for the first time on the next course, i. e. 90 course 19, Fig. 5. This is the situation on gores other than the one having loopers rounds 18 knit before course 19.

By thus taking down the hatband needles first the last needle to knit in the ever active 95 group is the first to knit on course 20 and a float thread is avoided on the next course.

The beret cap is of the usual shape, namely a crown from which the cap radiates to the maximum diameter and a comparatively short portion contracting therefrom to the hatband. The cap is composed of a plurality of segments or gores each tapered at both ends and interknit with its neighbors from one end to the other. I prefer to taper each 100 end of a gore at one side only. I make the widest part of each gore—which corresponds to the maximum diameter of the cap—much nearer the hatband end than the crown. This aids in giving the correct shape to the hat. I also make the taper at the hatband end 105 shorter and make this end 15 very blunt instead of a point, the blunt ends of all the gores constituting the hatband of the cap. The gores are knit in such a manner that the ends 15 are selvedge edges. The crown end 16 of each gore is tapered to a point each 110 consisting of a single loop. These loops form a small opening in the finished hat which can be used to fasten in a tassel or other ornament. The first and last gores are knit with loopers 115 courses 18 in order that they may be looped together after the knitting is completed. For the sake of clarity a single row of 120 stitches are hereafter termed a "course" and the course of stitches joining the two gores together will be termed a "cast-off course." In the example shown in the drawings the cast-off course 19 begins at the hatband end 125 and runs to the crown end 16, the knitting 130

in Fig. 5 proceeding from the bottom to the top of the figure and the courses from crown to hatband being the ones knit in a clockwise direction as viewed in Fig. 2. The small arrows in Figure 5 indicate the direction of knitting in the courses in which they are placed.

As already intimated in making a cap according to applicant's new process the machine is operated in a reciprocatory manner to knit in integral succession to each other a plurality of shaped segments extending from crown to the hatband of the hat, a maximum length of some or all of the segments being equal to the length of a course knit on substantially all the needles in the machine. This method of knitting the cap makes it possible to obtain a beret cap on the ordinary seamless hosiery machine by having the machine knit a series of such segments in the manner hereinafter described and having loopers courses knit prior to the first segment or gore and after the last segment or gore of the hat, these loopers courses being looped together by a subsequent operation.

In order to knit these loopers courses 18 it is desirable to throw the up picks 650, 651 out of action. This is done by means of a cam 504 on the main pattern drum 120 connected to the right hand pick 650 by one of the usual thrust rods 460 and an extension 505.

In order that a plurality of these segments constituting the cap may be knit in integral succession by continuous operation of the machine, the cams 501, 502 are repeated on the surface of the main pattern drum 120 in direct succession to each other as many times as there are to be segments in the cap so that the machine will repeat a cycle of operations as many times as necessary for the making of one cap and will then knit other caps in stringwork.

I have found it advisable to provide guard means to keep the segments already knit from crowding up in the fabric tube to an extent which would permit the previously knit segments to crawl up the needles and get caught in the sinkers. I would prefer to form this guard in the form of a dished disc or segment 503 extending around the majority of the circumference of the cylinder and to flute the edge of this dished guard so as to provide a plurality of different points at which the fabric is restrained downwardly.

It might also be noted that the switch cam 415 is operated from the vertical gravity rod 216 as has heretofore been known but that the manner and time of its operation are novel. Thus it is desired to keep the switch cam from ever raising needles out of action as a group when making the particular shape of segments shown in the drawings and I have therefore provided a rest or shoulder 506 underlying the free end of the switch cam 65 which prevents the switch cam from ever

dropping below a horizontal or level position, this level position being at such an elevation as to permit needle butts at the active level to pass underneath it. The connection between the vertical gravity rod and the switch cam includes a finger 218 overlying the tail 70 of the horizontal axis of the switch cam and permitting the gravity rod to move vertically downward after the switch cam has reached its level position and is restrained from turning further downward. This connection between the switch cam and the gravity rod is so adjusted that when the gravity rod is in its uppermost position under the control of its high cam 501 the switch cam is in its uppermost or active position. When the gravity rod is under the control of the knitting cam 502 or is on the surface of the drum, the switch cam is in its horizontal or idle position.

It is necessary to drop the switch cam from its uppermost position to this level position and to put the widening picker 680 out of action at the end of the knitting of the selvage portion of each segment and this must occur at the end of a clockwise movement. The ordinary mechanism for racking the main pattern drum 120 for this purpose is generally adjusted in such a manner that the pattern drum is standing still at this time, and I therefore employ other mechanism to give the main pattern drum this particular rack. This mechanism consists of a cam 507 on the main drive shaft of the machine which—by means of a pawl 509 on lever 510—gives one of a series of cams 511 the 90 main pattern drum a kick at just the desired moment under control of lugs 508 controlling the lever 510 as heretofore known.

The construction of the machine having been described its operation will now be set forth. It is first necessary to make a sufficient number of loopers rounds or courses 18 on all the needles including the blind needle by means of reciprocatory knitting and in order to prevent narrowing, the up picks 650, 651 are thrown out of action by means of the cam 504 on the main pattern drum. During this time the gravity rod 216 has been on the pattern drum 120 and the widening picker 680 has not been active. The machine knits a plurality of loopers courses 18 ending with a course in the clockwise direction from the crown to the hatband. Immediately thereafter course 19 from the hatband to the crown is knit and the pattern drum 120 is given a rack which places the widening picker 680 in operative position and frees the narrowing picks 650, 651 from the influence of the cam 504. This occurred just after the completion of the previous counterclockwise movement and just after the so-called blind needle had passed the right hand stitch cam 360. The first needle to be raised therefore is the end needle of the crown group,

i. e. the needle 21, but the widening picker 680 does not lower this needle because the needle approaches the picker from the right hand side and that widening picker is not notched but is rounded off and allows the needle to slide by it without lowering same. The repeated reciprocation of the machine will therefore begin the narrowing on the crown end as shown in the drawings. In the meantime the blind needle is being raised at the beginning of each counter-clockwise movement by the right hand up pick 651 and is being lowered again at each counter-clockwise oscillation by the widening picker 680 as that counter-clockwise movement nears its end. It will therefore be obvious that the blind needle prevents narrowing at the hatband end of the segment. This prevention of narrowing at the hatband end of the segment gives the selvedge which forms part of the hatband of the completed cap and in addition I have discovered that the use of the blind needle provides an especially good selvedge. By raising the blind needle before the hatband group of needles pass through the knitting cams the yarn is wrapped around the blind needle and the subsequent lowering of that blind needle by the widening picker not only permits the knitting of all the needles at the hatband end on any desired number of courses to make the selvedge but it also means that when the blind needle is lowered by the widening picker the loop on that needle is cast off leaving a big loop on the adjacent needle. It also avoids casting off at the selvedge on every other course. This makes the selvedge very elastic and rolls the edge somewhat back, a desirable characteristic for the selvedge of a beret cap. It will therefore be obvious that this process of knitting automatically provides an extremely good form of selvedge for the hatband of the cap and that since the plurality of segments which constitute the cap are knit in integral succession of each other a continuous integrally knit hatband having very desirable characteristics results from applicant's process.

The knitting of course 20 will be obvious from the description of the location of the switch cam. The gravity rod 216 is momentarily raised by the high cam 501 at course 20. When the selvedge portion of the segment is completed and the narrowing at the hatband end is to begin, the special rack is given by the cam 507, dropping the gravity rod 216 to the surface of the main drum 120, putting the widening picker 680 out of action. The effect of the up pick 650 on the blind needle is therefore no longer nullified.

The process herein described, broadly considered, and the product, form the subject-matter of my copending application for patent, Ser. No. 455,393, filed May 24, 1930.

and the narrowing takes place at the hatband end.

I claim:

1. In a process for producing a knitted cap on a circular knitting machine by reciprocatingly knitting the knitting of a plurality of segments whose longest courses correspond to the number of needles in the machine, shaping said segments by picking the needles and joining up the picked segments by moving the needles in the opposite direction as a group, in combination with the step of knitting a portion of the hatband end of each segment without narrowing or widening to form a selvedge. 70 75 80

2. A circular knitting machine for knitting caps comprising a needle cylinder, a partial circle of independent needles therein, and means adapted to reciprocate said cylinder, in combination with means adapted to cause the knitting in integral succession of a plurality of segments whose maximum length corresponds to said partial circle of needles and to the distance from crown to hatband of the cap, picker means adapted to shape said segments by throwing needles out of action from both ends of the segment, and control means for said picker means adapted to prevent narrowing at one end of the partial circle of needles. 90 95 100

3. A circular knitting machine for knitting caps comprising a needle cylinder, a partial circle of independent needles therein, and means adapted to reciprocate said cylinder in combination with means adapted to cause the knitting in integral succession of a plurality of segments whose maximum length corresponds to said partial circle of needles and to the distance from crown to hatband of the cap, and picker means adapted to shape said segments by throwing needles out of action from both ends of the segment and other means adapted to throw inactive needles into action as groups. 100 105 110

4. In a circular knitting machine for knitting circular articles a needle cylinder, a partial circle of independent needles corresponding to the length of the article from center to edge, means for knitting reciprocatorily in integral succession a plurality of segments of said article in combination with means adapted to taper the segments at both ends by picking a different number of needles out of action at each end. 115 120

5. In a circular knitting machine for knitting circular articles a needle cylinder, a partial circle of independent needles corresponding to the length of the article from center to edge, means for knitting reciprocatorily in integral succession a plurality of segments of said article in combination with means for rendering successive needles inactive recurrently and other means adapted to render idle needles active in a group. 125 130

6. In a circular knitting machine for knitting circular articles a needle cylinder, a partial circle of independent needles corresponding to the length of the article from center to edge, means for knitting reciprocatorily in integral succession a plurality of segments of said article in combination with means adapted to pick needles up on oscillations of the cylinder in both directions and other means to pick needles down on movements in one direction only said last mentioned means being adapted to function during only part of the picking-up of the needles. 70
7. In a circular knitting machine for knitting circular articles composed of a plurality of segments, a partial circle of independent needles corresponding to the length of the article from center to edge, knitting cams therefor, and means for causing relative reciprocation of the needles and knitting cams, in combination with means for narrowing the knitting from the center and edge on a plurality of segments of the article, and means for returning the inactive needles to activity in groups without clearing the needles. 80
8. In a circular knitting machine for knitting caps composed of a plurality of segments, a partial circle of independent needles corresponding to the length of the cap from center to edge, knitting cams therefor, and means for causing relative reciprocation of the needles and knitting cams, in combination with means for narrowing the knitting from the crown and hatband on a plurality of segments of the cap and other means for preventing narrowing at the hatband on some courses. 90
9. In a circular knitting machine for knitting caps composed of a plurality of segments, a partial circle of independent needles corresponding to the length of the cap from center to edge, knitting cams therefor, and means for causing relative reciprocation of the needles and knitting cams, in combination with a blind needle at the hatband end of the partial circle of needles, means for picking up needles at the crown and hatband end of the circle and other means for pulling said blind needle down after the yarn has been laid around it, said other means being active only on courses where is desired to make a selvedge for the hatband. 100
10. In a circular knitting machine for knitting caps composed of a plurality of segments, a partial circle of independent needles corresponding to the length of the cap from center to edge, knitting cams therefor, and means for causing relative reciprocation of the needles and knitting cams, long butts on the needles at the hatband end and medium butts on the needles at the crown end of the circle, in combination with means for picking needles up at each end of the 110
- circle and a down pick adapted to contact with the long butts and pull down needles from the hatband end but to allow free passage to medium butt needles. 120
11. In a circular knitting machine for knitting circular articles composed of a plurality of segments, a partial circle of independent needles corresponding to the length of the article from center to edge, knitting cams therefor, and means for causing relative reciprocation of the needles and knitting cams, in combination with means for narrowing the knitting from the center and edge on a plurality of segments of the article, and means for returning the inactive needles to activity in groups without clearing the needles, and a guard inside said partial circle having an irregular edge offering downward pressure to the knitted fabric at a plurality of points. 125
12. In a process for producing a knitted cap, the steps of knitting by reciprocation in integral succession a plurality of segments whose courses extend from hatband to crown, there being a selvedged knit on the hatband end of each segment, and drawing a bight of yarn around the end needle at the selvedge on each reciprocation and throwing the bight off said end needle without knitting it. 130
13. In a process for producing a knitted cap on a circular knitting machine, the steps of knitting by reciprocation a segment of the cap whose length from crown to edge of the cap corresponds to the knitted course, shaping the segments by throwing needles out of action, the shaping of one end being begun subsequent to the beginning of the shaping of the other end, and subsequently throwing idle needles into action as a group. 135
- In testimony whereof I have signed my name to this specification. 140

CERTIFICATE OF CORRECTION.

Patent No. 1,843,101.

Granted January 26, 1932, to

CHARLES W. STOUT.

It is hereby certified that error appears in the printed specification of the above numbered patent requiring correction as follows: Page 4, lines 66 and 67, strike out the words "and the narrowing takes place at the hatband end." and insert the same after the word "nullified" in line 61; and that the said Letters Patent should be read with this correction therein that the same may conform to the record of the case in the Patent Office.

Signed and sealed this 1st day of March, A. D. 1932.

**M. J. Moore,
Acting Commissioner of Patents.**
